STENCILING METHOD AND APPARATUS

John C. Smith and George H. Campbell, Monaca,
Pa., assignors to Solar Laboratories, Monaca,
Pa., a corporation of Pennsylvania

Application July 9, 1932, Serial No. 621,628

3 Claims. (Cl. 101—123)

Our invention relates to a stenciling method and apparatus, and particularly to the lettering and decorating of articles of glassware, and various other objects.

5 Our invention has for its object the provision of an improved method and apparatus whereby articles may be more rapidly lettered or decorated than by various methods heretofore employed, and with less danger of smudging the paint or 10 other decorating material on the surface of the article being operated upon.

Some forms of apparatus for practising our 15 invention are shown in the accompanying drawing, wherein Figure 1 is a sectional view through one form of stenciling apparatus; Fig. 2 is an end view of the structure of Fig. 1; Fig. 3 is a plan view thereof; Fig. 4 shows a manner in which the stencil sheet may be connected to the frame of Fig. 1; Fig. 5 shows an inverted plan view of the 20 stencil sheet; Fig. 6 shows a fragmentary plan view of a modified form of stenciling apparatus, and Fig. 7 is an elevational view thereof, partly in section.

While we hereinafter describe our invention in 25 connection with screen stenciling, it will be understood that other forms of stenciling may be employed, and that instead of applying stenciling ink to the articles, they may be coated with an acid-resistant material when the articles to be 30 etched are placed in an acid bath. Also, they may be similarly coated with a material which will be resistant to sand-blasting, in those cases where the uncoated portions of the articles are to be subjected to a sand-blast.

35 In the present case, we show the procedure followed in lettering glass jars or bottles 8 by ink pressed through a screen stencil which may be of any well-known form, but is here shown as consisting of a parchment sheet 9 and a silk or other 40 fibrous sheet 10, the sheets having perforations arranged to form the word "Salt." The perforations are preferably so closely spaced that the ink forced therethrough against the articles 8 will combine to present a substantially unbroken appearance on the faces of the jars.

The sheets 9 and 10 are secured to a frame 11 45 that has hinged connection with a box 12 which is open at its ends and provided with bars 13 and 14 that serve to define a passageway through the box for the jars 8. A stop member 15 of L shape is pivotally connected to the bottom board of the box 12, and has its end 16 extending through a perforation in the bar 13. At its pivot, 50 the latch or stop 15 has an extension 17 to which

is connected one end of a spring 18 whose other end is anchored at 19 to the box.

The stop 15, therefore, has its end 16 yieldably held within the channel formed by the bars 13 and 14, so that it will serve as a stop member for the jars being pushed through the box. The stop 15 has an extension 20 that is curved or inclined at its outer end, and normally overlies the entrance to the box, so that when a jar is being pushed into the box it will shift the lever 20 laterally, causing the latch 15 to be withdrawn against the tension of the spring 18, thereby removing the stop extension 16 from the passageway between the bars 13 and 14, and permitting the jars within the box to be advanced.

As soon as the entering jar passes the bent end 20 of the lever, such lever can swing back to the position shown in Fig. 3, thereby allowing the stop member 16 to enter the passageway in the box and limit movement of the jar which is then 25 approaching the mid portion of the box.

The lettering on the stencil is positioned above the central portion of the box, and the stop members 16 serve to center or position each jar in the proper location beneath the stencil sheet. A 30 squeegee 22 having a rubber edge, of somewhat the usual form, is employed for forcing ink from the top surface of the stencil sheet 10 through the letters of the stencil to the jars. If the upper surfaces of the jars are flat, the rubber blade of the squeegee may be fairly stiff, while if the surface of the jar is of uneven contour, better results would be secured by having the stencil rubber comparatively soft and flexible. Bars 23 are secured across the frame 11 to serve as stop and 35 guide members for the squeegee when it is being moved back and forth on the stencil sheet.

The stencil frame 11 is mounted at such height relative to the jars 8 that there is some clearance between the stencil sheet and the upper surface 40 of the jars, thereby avoiding smearing or smudging of the ink on the jars while they are being advanced beneath the stencil. The stencil sheet may conveniently have such flexibility or looseness on the frame that the clearance space may 45 be one-eighth inch, for example, the sheet, of course, being pushed into contact with the jars by the pressure on the squeegee, while the jars are stationary.

The clearance space can, of course, be varied 50 to suit conditions, and can be greater where the area of the stencil sheet is greater than shown in the drawing. If the sheet is made of such area as to permit of greater clearance space between it and the articles being stenciled, it will be seen 55

that articles of various dimensions may be stenciled on the same apparatus.

Again, articles of smaller sizes than those shown on the drawing can be stenciled in the apparatus here described, by inserting filler strips on the bottom of the channel formed by the bars 13 and 14, to permit such smaller articles to be moved through a path closer to the stencil sheet than if they rested directly on the bottom board of the box 12.

Referring now to Figs. 6 and 7, we show a rotatable carrier for advancing the jars beneath a stencil frame 25, which frame may correspond to the frame 11, and carry a stencil sheet in the same manner. This carrier consists of what is in effect a turn-table 26 that is rotatably supported in a frame 27. The table has a spindle or shaft-like extension 28 that is journaled in the frame 27, and which carries at its lower end a ratchet wheel 29 that is rigidly secured thereto. A pawl lever 30 is loosely and rotatably supported on the lower end of the shaft 28 and carries a pivoted pawl 31.

A pull rod 32 is connected at one end to the pawl lever 30, and at its other end to a rocking lever 33. The lower end of the lever 33 is pivotally connected to the base of the frame 27, and a link 34 has one end pivotally connected to the lever 33, and its other end connected to a bell crank lever 35, which has a treadle 36 and is pivotally mounted upon a supporting member 37.

It will be seen that when the treadle 36 is depressed by the foot of the operator, the pull rod 32 will be thrust toward the shaft 28, thus rocking the pawl lever 30 and causing the pawl, which is spring-held against the periphery of the ratchet 29, to rotate the ratchet and the table 26 one step. Upon release of the treadle 36, the levers will be returned to retracted position, either through the weight of the lever 33 or by a suitable spring.

The table is provided on its upper surface with laterally-spaced bars 38 and 39 that serve to form a channel or pocket for the jars. The jars may be loaded onto the table at the station 40, it being understood that the table is advanced step-by-step in a clockwise direction by operation of the treadle 36. Each time a lettered jar is taken off, a blank jar is put in its place, and the operator of the squeegee will depress the treadle 36

to intermittently advance the table to bring the jars, one by one, beneath the stencil 25.

The outer end of the pull rod 32 has pin-and-slot connection with the upper end of the lever 33, so that it can be adjusted at various vertical positions to permit of varying its length of stroke and consequently the distance which the table will be rotated upon each actuation of the treadle 36. The points at which jars carried by the table will be stopped with respect to the stencil can 10 thereby be altered at will.

In both forms of apparatus above described, it will be seen that the articles can be very rapidly imprinted, because they can be advanced step-by-step, through a given path beneath the stencil screen, thus avoiding the necessity of lifting the screen and placing each article beneath it as in the case of methods heretofore employed.

We claim as our invention:—

1. Stenciling apparatus comprising a guideway 20 for articles to be stenciled, a stencil sheet or the like positioned above said guideway, a stop member normally positioned to limit movement of an article past the said stencil, and a tripping device positioned to be operated by an article 25 entering the guideway and serving to withdraw the said stop member to inoperative position.

2. Stenciling apparatus comprising a guideway for articles to be stenciled, a stencil sheet or the like positioned above said guideway, a stop member yieldably held in position to limit movement of an article past the said stencil, and a tripping device positioned to be operated by an article entering the guideway, and serving to withdraw the said stop member to inoperative position. 35

3. Stenciling apparatus comprising a guideway for articles to be stenciled, a stencil sheet or the like positioned above said guideway, a latch bar having a stop member normally extending into said guideway below the stencil sheet, a cam 40 member carried by the latch bar and normally disposed in the path of articles entering the guideway so as to be deflected by said articles sufficiently to withdraw the stop member from the guideway, and means for yieldably maintaining 45 the latch bar and said stop and cam members in inwardly projected position.

JOHN C. SMITH.
